ATTORNEY.

UNITED STATES PATENT OFFICE.

DAVID FETTERS, OF BALTIMORE, MARYLAND.

CAR-COUPLING.

SPECIFICATION forming part of Letters Patent No. 254,472, dated March 7, 1882.

Application filed December 6, 1881. (No model.)

To all whom it may concern:

Be it known that I, DAVID FETTERS, of Baltimore city, State of Maryland, have invented certain new and useful Improvements in Car-Couplings; and I hereby declare the same to be fully, clearly, and exactly described as follows, reference being had to the accompanying drawing, in which the device is illustrated in central vertical sectional view.

10 My invention relates to that class of car-couplings in which the pin is sustained by a catch or detent, which latter is released by the entering link and the pin is allowed to fall, the design being to avoid the necessity for directing the link by hand into the buffer.

15 My said invention has for its object to provide a simple attachment for sustaining the pin or link, as the case may be, of such construction as to be readily applied to the buffer, 20 not liable to be battered or worn, and readily renewable when wear eventually occurs.

In the drawing, A is the draw-head or buffer, having a flaring mouth of the usual form, and B is the coupling-pin. Within the draw-head is suspended from a pivot, D, a catch, C, having an arm, c, and recess c', as shown. The catch is slotted at d, so as to have a slight vertical movement when necessary. A recess, b, is formed in the draw-head behind the catch, 25 whereby the latter may swing out of the way as the link E enters. The catch normally hangs vertical, as shown, in which position its

arm c is below the upper pin-hole, a, and serves to sustain the pin. The link is held in the opposing draw-head in the position shown in dotted lines, its end being placed below the catch c' of the part C, which latter is thrust backward until it abuts against the rear face of the recess b. In this position the part C sustains the link in proper position to enter the other draw-head, and facility is afforded for a play of the catch in order to prevent its injury should the link not enter the draw-head fairly. The other end of the link enters the opposing draw-head, and, pushing back the catch C, releases the 45 pin, which falls into the lower hole, a, and secures the link.

The device may be attached to the draw-head at a trifling cost, is not liable to get out of order, and answers the desired end most efficiently.

Having thus described my invention, what I claim is—

In combination with the draw-head having recess b, the gravity-catch C, of shape conforming thereto, pivoted at its upper end, and provided with an arm, c, for sustaining the pin, a recess, c', for holding the link, and a slot, d, through which the pivot-pin passes, substantially as set forth.

DAVID FETTERS.
